DESIGN FOR A DOUBLE BAG FOR HOT WATER OR ICE

Frances E. Woodruff, Orange, N. J.

Application August 28, 1944, Serial No. 115,064

Term of patent 14 years

(Cl. D83—1)

To all whom it may concern:

Be it known that I, Frances E. Woodruff, a citizen of the United States, residing at Orange, in the county of Essex and State of New Jersey, have invented a new, original, and ornamental Design for a Double Bag for Hot Water or Ice, of which the following is a specification, reference being had to the accompanying drawing, forming a part thereof.

Figure 1 is a top plan view of a double bag for hot water or ice showing my new design; and

I claim:

The ornamental design for a double bag for hot water or ice, as shown.

FRANCES E. WOODRUFF.
